(57) **CLAIM**

The ornamental design for a packaging case for compressed tissue, as shown and described.

DESCRIPTION

FIG. 1 is a perspective view of a packaging case for compressed tissue according to the present invention.

FIG. 2 is a front view of the packaging case of FIG. 1. A rear view, a left side view, and a right side view would be identical to the front view.

FIG. 3 is a top view of the packaging case of FIG. 1; and, FIG. 4 is a bottom view of the packaging case of FIG. 1.
